UNITED STATES PATENT OFFICE

ARTHUR J. RAY AND CLARENCE E. LOMAX, OF CHICAGO, ILLINOIS, ASSIGNEES, BY
MESNE ASSIGNMENTS, TO AUTOMATIC ELECTRIC INC., OF CHICAGO, ILLINOIS, A
CORPORATION OF DELAWARE

STREET TRAFFIC REGULATING SYSTEM

Application filed May 28, 1925. Serial No. 33,320.

This invention relates in general to street traffic control systems, more particularly to such systems in which several regulating stations are automatically operated from one common control station.

One of the objects of our invention is to provide a new and improved traffic control system in which a number of traffic regulating stations are operated over a pair of telephone or telegraph cable conductors, leading out from a central control station.

A further object of our invention is to provide a traffic control system that will be certain in its operation and inexpensive to install and maintain.

A further object of our invention is to provide circuit means so that any traffic regulator can be cut off from the central control station, without effecting the other regulators on the circuit, and operated manually by the patrolman.

A further object of the invention is to provide a central control station timing mechanism which is arranged to quickly change the time interval allowed to a traffic route.

A further object of the invention is to provide a means whereby the entire control circuit may be rendered inoperative during intervals when the traffic is so light as to need no regulation. The drawings, comprising Figs. 1 and 2, show our invention in two forms.

Referring to Fig. 1, the traffic regulator TR, which may be any well known traffic tower or signal post in common usage at street intersections, is arranged in accordance with the objects of this invention to be controlled over the cable conductors 37 and 38 from the central control station CS, in accordance with the cam setting of the program clock PC. The traffic regulator TR comprises the usual three lamps, an amber colored lamp to denote a change in traffic, a red lamp to denote stop, and a green lamp to denote go ahead. The regulator TR, one of a plurality of regulators attached to the cable pairs 37 and 38, is directly controlled by means of the polarized relay 1, when the main switch 30 is closed. At the control station the program clock, which may be any of

the well known program clocks, controls the relays 4 and 5 by means of circuits completed by the cams 32 and 33. In practice, one circuit would probably contain as many traffic regulators as are needed to regulate the traffic on one thoroughfare. This clock may have other cams, not shown in Fig. 1, attached to the shaft to control other circuits as required to control traffic on streets crossing the main thoroughfare. These cams can be staggered with respect to 32 and 33 in the manner best suited to the particular traffic conditions encountered. Each circuit will have two relays, such as 4 and 5, and the associated cam springs individual to it.

Referring to Fig. 2, there is shown a modification of our invention in which the traffic regulator is essentially the same as before, but the program clock at the control station has been replaced by the timing mechanism TM. Single stroke gongs 58 and 59 have been added to the traffic regulator TR and arranged to ring once when the traffic changes, thereby giving an audible signal as well as a visual signal to denote the change. Other changes in the modifications of Fig. 1, which are shown in Fig. 2, will be pointed out in connection with the detailed description which follows hereinafter.

In the drawings we have shown a plurality of batteries to indicate a source of current. In Fig. 1 the source of current at the traffic regulator TR and at the control station CS should be direct current. The commercial 110 volt direct current available in many localities would be suitable to operate this arrangement of our invention. The modification shown in Fig. 2 requires that direct current be available at the control station CS, while the source of current available to the traffic regulator TR may be either direct or alternating current.

Having thus described our invention in general, we will now proceed with the detailed description of its operation. In Fig. 1, with the cams 32 and 33 in the position shown the circuits for control relays 4 and 5 are open, and the polarized relay 1 is in its normal position. A circuit may be traced from ground through spring 20 and its break contact, 100

through the signal lamp 35, through spring 21 and its break contact, to grounded battery. Signal lamp 35, which is lighted over the above traced circuit, is an amber light to 5 designate that a traffic change is about to take place. The program clock PC advances the cams 32 and 33 in the direction shown by the arrow, and after an interval operates the spring 29, closing a circuit from ground, 10 through spring 29, through the winding of relay 5 to grounded battery. Relay 5 energizes and closes a circuit traceable from ground through spring 27, over conductor 38, through the winding of relay 1 and other similar relays 15 in parallel, through conductor 37, through spring 26 to grounded battery. The current flowing over the control circuits 37 and 38 is in such a direction as to operate relay 1 to close springs 22. The traffic tower 20 TR being under the control of the control station CS will have its individual switch 30 closed so that when relay 1 operates, a circuit is closed from ground through switch 30, through springs 22, through the winding of 25 relay 2 to grounded battery. Relay 2 energizes over this circuit and breaks the circuit for the signal lamp 35 which was closed through spring 20 and its break contact, and at the same time closes a circuit from ground 30 through spring 20 and its make contact, through signal lamp 34, to grounded battery. Signal lamp 34, being red, denotes traffic must stop. The program clock PC continues to advance the cams and after an interval 35 opens the spring 29, thereby interrupting the circuit of relay 5 which falls back and opens the circuit of relay 1. Relay 1 restores and opens the circuit of relay 2 which on falling and back extinguishes the red signal lamp 34 and 40 again lights the amber light 35 to denote a traffic change. The cams 32 and 33 continue to advance and after an interval close the cam spring 28, completing a circuit from ground, through spring 28, through the winding of relay 4 to grounded battery. Relay 4 45 energizes and closes a circuit traceable from ground through spring 25, over conductor 37, through the relay 1 and other similar relays, conductor 38, through spring 24 to grounded 50 battery. It will be noted that the direction of current flow in the conductors 37 and 38 is now in the reverse direction to what it was when the circuit was closed by the relay 5. 55 The polarized relay 1 responds to this current to close the spring contacts 23, thereby closing a circuit from ground, through the switch 30, through springs 23, through the winding of relay 3 to grounded battery. Relay 3 energizes and at spring 21 opens the 60 previously described circuit of the signal lamp 35 and closes the circuit of signal lamp 36 which is traceable from ground, through the lamp 36, through the make contact of 65 spring 21, to grounded battery. The lamp 36 is a green lamp and denotes that the traffic may now proceed.

The above cycle of operations will continue as long as the switch 30 of the traffic regulator remains closed. In the event that traffic conditions become such that the patrolman deems it necessary to manually operate the traffic regulator he may segregate it from the control control station by opening the main switch 30. This disconnects the ground supply to the springs 22 and 23 of the polarized relay 1, but does not in any way effect the operation of the polar relay, nor does it effect the operation of the polar relays of any other traffic regulators which are on the same circuit 37 and 38. When the patrolman opens the switch 30 both relays 2 and 3 are held in normal position and the amber light 35 is lighted continuously, notifying the traffic to approach the crossing with caution. The patrolman may then manually direct the traffic as he sees fit, or he may manually control the traffic regulator by manipulation of the switch 31. Assuming that he wants to stop traffic, he will throw the switch 31 to the right, closing a circuit from ground through the switch 31, through the winding of relay 2, to grounded battery, energizing the relay 2 to bring up the red light, as hereinbefore described. When he desires to change the traffic he merely opens the switch 31, causing the red light to extinguish and the amber light to light again. When the patrolman desires to send traffic ahead he closes the switch 31 to the left, closing a circuit for the relay 3, which operates, as hereinbefore described, to extinguish the amber light and light the green light 36, sending the traffic on.

The length of time that traffic moving in either direction is allowed depends upon the rate at which the cams 32 and 33 are rotated, as well as upon the shape of the cams themselves. The shaft of the program clock may be provided with other similar cams to control other streams of traffic over a circuit similar to that shown in Fig. 1.

Referring now to the modification shown in Fig. 2, the program clock has been replaced by a timing mechanism which is driven by the timing interrupter 11. When the traffic regulators are to be controlled from the central control station the key 44 is in normal position as shown in Fig. 2, and the circuit is closed from ground to the right hand break contact of the key 44, through the winding of interrupter 11, through the resistance 11', to grounded battery. Relay 11 energizes and attracts its armature to the left, closing the contacts 54' which short out the winding of the relay by the obvious circuit. The relay then deenergizes and, as the armature returns, closes the contacts 54, closing a circuit from ground at spring of key 44, contact 54 to the winding of motor magnet 10, to grounded

battery. Motor magnet 10 energizes and prepares its armature to advance the wipers 55 and 56. The switch mechanism TM is of the well known rotary switch type such as that shown on page 57, of the third edition of Automatic Telephone Practice, by Harry E. Hershey. The wipers of this switch are advanced when the driving magnet releases and the armature returns to normal rather than when the armature is operated to the energized position. The interrupter 11 periodically closes the circuit to the motor magnet 10, advancing the wipers 55 and 56 in the direction shown by the arrows. With the wipers in the position shown in Fig. 2, a circuit is closed from ground, through wiper 55 and its associated bank contacts, through the winding of relay 7 to grounded battery. Relay 7 energizes over the above traced circuit and closes a circuit from ground through spring 47, over conductor 64, through the contacts of key 44, through the winding of polarized relay 6 of the traffic regulator TR, through the springs of key 45, over conductor 63, to make contact of spring 46, to grounded battery. Relay 6 responds to the current flowing in the above circuit and closes the spring 40, thereby establishing a circuit for the red signal lamp 60 which is traceable from ground, through springs of key 42, through spring 40, through the signal lamp, to grounded battery, with a multiple branch through the gong 58 to grounded battery. The red light is lighted and the gong 58 sounds once to give an audible and visual indication of the traffic regulation. When the motor magnet advances the wipers 55 and 56 to the next step, the circuit just traced for the relay 7 and including the wiper 55 is broken, allowing that relay to restore and to remove the potential from the conductors 63 and 64. Relay 6 restores and breaks the previously established connection for the signal lamp 60 and, at the same time, closes a connection for the amber signal lamp 61 which is traceable from ground through spring 42, through spring 40 and its break contact, through the lamp 61, through spring 41 and its break contact, through spring 43, to grounded battery. The amber light is lighted to denote that a traffic change is about to take place. The wipers 55 and 56 continue to advance until the wiper 55 encounters the bank contact *a*, at which time a circuit for relay 8 is closed from ground through spring 52 and its break contact, through wiper 55 and the fourth associated bank contact, through the winding of relay 8, to grounded negative battery. Relay 8 energizes over this circuit and closes a circuit traceable from ground, through spring 49, over conductor 63, through the springs of key 45, through the winding of relay 6, through the springs of key 44, over conductor 64, through spring 50 to ground battery. The current flow through the windings of relay 6 being in the opposite direction, the relay energizes and closes the springs 41, thereby breaking the circuit for the amber light 61 and closing the circuit for the green light 62, which may be traced from grounded battery, through spring 43 and its break contact, through spring 41 and its make contact, through the signal light 62 to ground, with a multiple branch through the gong 59 to ground. The green light 62 is lighted and the gong 59 sounded once to designate the change in traffic. The green light remains lighted while the wiper 55 is passing from bank contacts *a* to *b*. When the bank contact *b* is passed the circuit for relay 8 is opened by wiper 55 and that relay restores, restoring relay 6 which extinguishes the green light and again lights the amber light over the circuit hereinbefore traced.

If, at any time, traffic conditions become so that the intervals of red and green lights set forth by the timing wiper 55 of the timing mechanism TM, become inadequate and it is desired to lengthen one interval and to shorten the other, the attendant at the control station operates a push-button to close the contacts 57 and 57', thereby changing the timing interval. Operation of the push-button closes a circuit to the relay 9 when wiper 55 reaches the bank contact *j*, over a circuit traceable from ground, through spring 52 and its break contact, through wiper 55 now in engagement with bank contact *j*, through spring 57', and through the winding of relay 9 to grounded battery. Relay 9 then energizes and breaks the above traced circuit at spring 52 and its break contact, but establishes a holding circuit for itself from ground, through spring 57, through spring 53 and its make contact, and through its own winding to grounded battery. The energization of relay 9 disconnects the ground from wiper 55 and connects it to the wiper 56 so that the relay 8 will be energized when the wiper 56 is in engagement with contacts *e* to *f*, and the relay 7 will be energized when the wiper is in engagement with contacts *g* to *h*. It will be seen that by this means the change in the timing interval can be readily made. Furthermore, that change will not take place until both the red and green lights have burned during the full time of the interval then in use, that is, the change takes place during the time that the amber light is lighted. When the push button, holding springs 57 and 57', is released to return the operation again to wiper 55, the locking circuit of relay 9 is interrupted. However, to insure that the change of the timing interval will not take place until both red and green lights have burned during their full time of use, the springs 48 and 51 are provided so that if either relay 7 or 8 is energized, relay 9 will be held up from ground on these contacts until wiper 56

opens the circuits of relay 7 or 8, whereupon springs 48 or 51 will permanently open the circuit of relay 9.

In many localities, night supervision of traffic is not necessary, in which case the attendant at the control station merely operates the key 44 which opens the circuit of all the polarized relays, such as 6, and also opens the circuit through the interrupter relay 11, thereby bringing the equipment to rest with the amber lights lighted throughout the system.

If, for any reason, the patrolman desires to manually control the traffic at a given intersection rather than to have it controlled from the common control station, he may isolate that particular traffic regulator by operating the key 45, without effecting the other regulators on the circuit. The patrolman may then leave the amber light lighted steadily and control the traffic manually, or he may manually control the traffic regulator by operating key 42 to extinguish the amber light and light the red light, restore the key 42 to relight the amber light and extinguish the red light and then operate key 43 to again extinguish the amber light and light the green light.

From the above description it is evident that we have invented a new and useful traffic regulating system, two modifications of which are shown and explained. There are many modifications and improvements which will be evident to those skilled in the art, and while we have chosen to show our invention with a particular arrangement of equipment we do not wish to be limited to the specific disclosure herein.

What we consider new and desire to have protected by Letters Patent is pointed out in the appended claims.

What is claimed is:

1. In a device for transmitting alternate polarities of current, conductors associated therewith, a progressively movable switch including a wiper and a set of bank contacts associated therewith, means for advancing said wiper over said bank contacts at a predetermined rate of speed, and means responsive to the advancement of said wiper over one portion of said bank contacts for connecting a certain polarity of current to said conductors, and means responsive to the advancement of said wiper over another portion of said contacts for connecting the opposite polarity to said conductors.

2. In a device for transmitting alternate polarities of current, conductors, associated therewith, a progressively movable switch including a wiper and a set of bank contacts associated therewith, means for advancing said wiper over said bank contacts at a predetermined rate of speed, means responsive to the advancement of said wiper over one portion of said bank contacts for connecting a

certain polarity of current to said conductors for a predetermined time, and means responsive to the further advancement of said wiper over another portion of said bank contacts for connecting the opposite polarity to said conductors for the same time or a different period of time.

3. In a device for transmitting alternate polarities of current, conductors associated therewith, a progressively movable switch including a pair of wipers and a set of bank contacts associated with each wiper, means for advancing said wipers over said bank contacts at a predetermined rate of speed, only one of said wipers normally effective, means responsive to the advancement of said effective wiper over one portion of its associated bank contacts for connecting a certain polarity of current to said conductors for a predetermined period of time and responsive to the advancement of said wiper over another portion of said bank contacts for connecting the opposite polarity to said conductors for the same or a different period of time, means for disconnecting said normally effective wiper and rendering said other wiper effective, said second means responsive to the advancement of said other wiper over its associated bank contacts for connecting said polarities of current to said conductors for different predetermined periods of time.

4. In a device for transmitting alternate polarities of current, conductors associated therewith, a progressively movable step-by-step switching mechanism having two separate banks of contacts with a wiper for each set and each bank of contacts divided into two sets of multiply connected contacts, only one of said wipers normally effective, means for operating said switch to move said effective wiper over its associated two sets of multiple contacts to connect first one polarity and then the reverse polarity of current to said conductors for a definite time interval in accordance with the number of multiple contacts, and means for disconnecting said normally effective wiper and rendering the other wiper effective, said first means operating said switch to move said other wiper over its two sets of multiple bank contacts to connect said different polarities of current to said conductors in the same definite order but for different time intervals than said first wiper.

In witness whereof, I hereunto subscribe my name this 7th day of May, A. D. 1925.

ARTHUR J. RAY.
